UNITED STATES PATENT OFFICE.

WILLIAM MARK SCRUGGS, OF MONTEAGLE, TENNESSEE.

GUN-CARTRIDGE.

SPECIFICATION forming part of Letters Patent No. 700,983, dated May 27, 1902.

Application filed September 29, 1900. Serial No. 31,580. (No model.)

To all whom it may concern:

Be it known that I, WILLIAM MARK SCRUGGS, a citizen of the United States, residing at Monteagle, in the county of Marion and 5 State of Tennessee, have invented a new and useful Gun-Cartridge, of which the following is a specification.

This invention relates to improvements in cartridges for firearms; and its object is to 10 provide an improved construction of cartridge, in which the cap may be quickly and conveniently positioned, said cartridge carrying means for cleaning the barrel of the firearm and provided with an improved projectile and with means for relieving the jar 15 or jumping of the gun when the same is fired.

With the above object in view the invention consists in the novel features of construction hereinafter fully described, particularly pointed out in the claim, and clearly illustrated by the accompanying drawing, which is a longitudinal sectional view of a cartridge embodying my invention.

Referring now more particularly to said 25 drawing, A designates the shell of the cartridge, having a tapering recess to receive the cap B, the side walls of which are tapered, as clearly illustrated. By forming the cap with a slight taper and providing the shell with a 30 corresponding recess said cap may be very conveniently and quickly positioned in the shell in loading.

C designates a plug formed of pulp or fabric and inserted in the shell abutting against 35 the closed inner end thereof. This plug has its outer face formed concave, as illustrated, and is provided with a centrally-disposed tapering opening to receive the cap. Positioned in the shell intermediate its ends is the cleaning device, consisting of an expanding wad D, formed of pulp or fabric and concaved in both 40 of its faces, as illustrated. The powder E is positioned between the plug C and the wad D, and will be retained in the shell in a mass, having both of its ends convexed.

F designates the projectile, which is formed

convexed at both of its ends, the inner end thereof fitting in the concaved outer face of the wad D. Formed in the inner end of said projectile is a cavity G, which makes the inner end of said projectile lighter than the outer end thereof. By making the inner end lighter the projectile does not deviate from a straight line when fired, as is the case with projectiles in which the rear end is the heavier 55 end.

When the cartridge is fired, the wad D expands and is driven forward, removing all dirt and powder from the gun-barrel which has accumulated therein. The plug C and the wad D having their opposing faces formed concaved, the powder positioned therebetween is retained in the shape of a cylindrical mass, having both its ends rounded. This relieves the gun of rear pressure and 65 prevents the jarring or jumping thereof when fired.

Having thus fully described my invention, what I claim as new, and desire to secure by Letters Patent of the United States, is—

A cartridge comprising a tapering shell and contracted at its forward end, a tapering plug fitted into the rear end of the shell and having the tapering opening adapted to receive the cap, the forward faces of said plug being 70 concaved and a projectile convex at both ends and fitting into the contracted end of the shell, the inner end of said projectile having a recess produced therein, and a wad arranged in contact with the rear end of the 75 projectile, said wad having its front and rear faces concaved and the explosive adapted to be contained in the shell between the concaved face of the plug and wad, said wad being secured at the juncture of the main portion of the shell and the contracted forward end, substantially as described.

WILLIAM MARK SCRUGGS.
